Primary Examiner — Mary Ann Calabrese(74) *Attorney, Agent, or Firm* — Temmerman Law; Mathew J. Temmerman(57) **CLAIM**

I claim the ornamental design for an illuminated nametag, as shown and described.

DESCRIPTION

FIG. 1 is a top, front right perspective view of an illuminated nametag showing my new design;

FIG. 2 is a top, back right perspective view thereof;

FIG. 3 is a front view thereof;

FIG. 4 is a back view thereof;

FIG. 5 is a top view thereof;

FIG. 6 is a bottom view thereof;

FIG. 7 is a right side view thereof; and,

FIG. 8 is a left side view thereof.

In the drawings, the broken lines illustrate environment and form no part of the claimed design.
